Attorney.

UNITED STATES PATENT OFFICE.

MARSHALL G. WHEELER, OF WINSTED, CONNECTICUT.

COFFIN-HANDLE.

SPECIFICATION forming part of Letters Patent No. 660,742, dated October 30, 1900.

Application filed October 12, 1899. Serial No. 733,377. (No model.)

To all whom it may concern:

Be it known that I, MARSHALL G. WHEELER, a citizen of the United States, residing at Winsted, in the county of Litchfield and State 5 of Connecticut, have invented certain new and useful Improvements in Coffin-Handles, of which the following is a full, clear, and exact description, whereby any one skilled in the art can make and use the same.

10 My invention relates to means for securing parts of a structure in place, involving a dowel provided with locking means, and while the particular object is to produce a coffin-handle in which the device is used a further object 15 includes its application to a wide class of structures in which a socket member and a dowel member are secured together.

20 My invention consists in a structure, as a coffin-handle, including a socket member, an attached member with a dowel or tenon to enter the socket, and an anchor projecting from the surface of the dowel; and it further 25 consists in the details of the several parts making up the structure and the combination 30 of such parts, as hereinafter described, and more particularly pointed out in the claims.

Referring to the drawings, Figure 1 is a front 35 view of a coffin-handle. Fig. 2 is a detail view of parts of the handle on enlarged scale and cut in section to illustrate the construction. Fig. 3 is a view in cross-section through the handle. Fig. 4 is a detail side view of a 40 dowel member provided with several anchors or barbs. Fig. 5 is a detail view of two members of a structure connected by a dowel or tenon with the anchor or barbs. Fig. 6 is a detail view showing a modified form of the 45 invention. Fig. 7 is a detail view showing another modified form of the invention.

50 In the accompanying drawings the letter *a* denotes a handhold, which is the rod forming part of a coffin-handle adapted to be grasped to support the coffin. This handhold is secured to the pivoted arms *b c*, which are supported in a suitable manner on a base plate or plates *d*. These parts are usually made of metal and, as a rule, of spelter or the like, which is ductile and of a somewhat fragile character. Such a handhold has been made 55 up of a tubular part *a'* and end pieces *a² a³*,

fastened together by a short inner reinforce or tube secured to the respective parts *a²* and *a³*, the joints being located at *e e'*.

My improved means for attaching the several parts of the handhold firmly together 55 and strengthening the whole involves the use of a filling-piece *f* of wood of a size and shape in cross-section to fit closely within the tubular main part of the handhold, with its opposite ends projecting beyond the tube. These 60 ends *f'* may be reduced in diameter to form a dowel or tenon to fit within a socket in the end pieces *a² a³*. Each end piece is preferably provided with a filling-piece *g* of wood, having a socket *g'*, into which the dowel or 65 tenon snugly fits. The end pieces are forced upon the ends of the rod *f*, and the meeting edges of the metallic parts of the handhold and end pieces or caps may be soldered together, as before.

70 In order to insure the firm engagement of the parts, an anchor-piece or barb *h*, of metal, is fixed in the tenon, so as to project a short distance beyond the surface, the barbs being flexible and resilient, so that they will turn 75 slightly backward, as to the projecting ends, and resist any attempt or tendency to pull the end piece out of the rod.

The anchor-piece or barb is preferably a piece of flat spring metal extending through 80 a transverse socket in the dowel or tenon, as shown in Fig. 3, the socket being relieved at the ends and back of the barb to allow it to bend over as the tenon enters the socket and to slope slightly backward, so as to catch into 85 the surface of the socket and resist any attempt to separate the parts.

In Figs. 4 and 5 of the drawings my invention is shown as applied to a socket member 1 and a dowel or tenon member 2, the member 3 serving, as shown in Fig. 5, to anchor the parts together. This fastening means may obviously be used in connection with glue or other means for attaching the parts together, or it may be used as the sole fastening means.

90 In Figs. 6 and 7 a modified form of the invention has been shown, in which in Fig. 6 the barbs *i*' are formed on a sleeve *i*, which 95 may be secured in any desired manner to 100

the filling-piece *f*, and in Fig. 7 the barbs *k*' are formed on a collar *k*, which is secured to the filling-piece in any desired manner.

While I have shown and described herein several means for carrying out the invention, it is to be understood that these means may be modified to a certain extent and yet come within the scope of the invention so long as the filling-piece contains barbs which will engage with the filling-piece in the end piece of the handhold in an attempt to separate the parts.

It is to be noted that by the use of my improvement a fastening is provided in which the members are securely fastened together without the use of nails, screws, glue, or the like and one in which the fastening means are invisible, thus presenting a neat and finished appearance.

20 I claim as my invention--

1. In combination in a coffin-handle having a metallic covering and including arms and a handhold secured to the arms, a filling-piece located within the handhold and extending beyond the ends thereof, an end piece, a filling piece located within the end piece and having a socket adapted to receive the end of the filling-piece in the handhold, and barbs for holding said parts in engagement.

2. In combination in a coffin-handle having a metallic covering and including arms and a handhold secured to the arms, an end piece, filling-pieces located within the handhold and end pieces and having sockets and dowels for engagement, and means for holding the end pieces in place.

3. In combination in a coffin-handle, the base-plates, the arms attached thereto, a handhold secured to the arms and comprising a tubular part with a filling-piece, end pieces, a 40 socket in the one part and dowels on the other part, the dowel being provided with projecting barbs, all substantially as described.

4. In combination in a coffin-handle including a base-plate, arms attached thereto, and a metallic handhold secured to the arms, a filling-piece within the handhold and extending beyond the ends, metallic end pieces, filling-pieces within the end pieces and having sockets for the reception of the ends of the 50 filling-piece of the handhold, and barbs located between said filling-pieces for securing the parts together.

MARSHALL G. WHEELER.
